United States Patent Office

Des. 233,764

Patented Nov. 26, 1974

233,764

TELEPHONE COMMUNICATIONS UNIT

Paul Marchese, Greenwich, Conn., assignor to
TIE Communications, Inc., Stamford, Conn.

Continuation of design applications Ser. No. 267,432, and
Ser. No. 267,462, both dated June 29, 1972. This
application Jan. 28, 1974, Ser. No. 437,397

Term of patent 14 years

Int. Cl. D14—03

U.S. Cl. D26—14 A

Fig. 2.

Fig. 3.

FIG. 1 is a front perspective view of a telephone communications unit showing my new design;

FIG. 2 is a left elevation view of the telephone communications unit of FIG. 1;

FIG. 3 is a rear elevation view of the telephone communications unit of FIG. 1; and

FIG. 4 is a front perspective view of a second modified embodiment of a telephone communications unit showing my new design;

This is a continuation of design applications, Ser. Nos. D. 267,432 and D. 267,462, filed June 29, 1972, both now abandoned.

I claim:

The ornamental design for telephone communications unit, substantially as shown and described.
